SNELLING MACHINE

Alexander Lauterbach, Washington Mills, N. Y.,
assignor to Horrocks-Ibbetson Co., Utica, N. Y.,
a corporation of New York

Application March 7, 1940, Serial No. 322,855

6 Claims. (Cl. 242—7)

This invention relates to a device for attaching a gut or other snell to a fish hook.

One of the objects of the invention is to provide an improved and simplified mechanism for controlling the operation of such a device in such a manner as to accurately control the winding of the binding thread over the hook shank and gut with simplified means of adjustment by means of which the length of the binding can be readily adjusted for various sizes of hooks.

A further object of the invention is the provision of simplified and more efficient means for holding the hooks in the machine during the binding operation together with simplified means for adjusting the device for different sizes of hooks.

A further object is the provision of improved and simplified means for accurately advancing the hook during the winding operation proportionally with the winding operation, so as to assure a uniform wrapping of the binding thread upon the shank, associated with adjustment means rendering the same adaptable to various sizes of hooks.

A further object of the invention is to consolidate and simplify in a unified mechanism the device for automatically stopping the machine at the conclusion of the winding operation, and the means for adjusting the length of the winding operation.

The invention consists in the novel construction, arrangement, and combinations of parts, hereinafter more particularly described and claimed.

Three sheets of drawings accompany the specification as part thereof, in which like reference characters indicate like parts throughout.

Figure 1 is a front elevation of the improved machine;

Figure 2 is a rear elevation of the improved machine;

Figure 3 is a plan view;

Figure 4 is a transverse vertical section taken on line 4—4 of Figure 3;

Figure 5 is a fragmentary longitudinal cross-section taken on line 5—5 of Figure 3;

Figure 6 is a fragmentary vertical cross-section taken on line 6—6 of Figure 4;

Figure 7 is a fragmentary vertical cross-section taken on line 7—7 of Figure 4;

Figure 8 is a fragmentary vertical cross-section taken on line 8—8 of Figure 4;

Figure 9 is a fragmentary perspective view of the hook receiving end of the main shaft, showing details of the hook engaging device.

Referring to the drawings, which illustrate a practical embodiment of the present invention, 1 indicates a substantially rectangular base upon which are mounted vertical standards 2—2 provided with suitable journals to receive a main rotary shaft 4 extending longitudinally of the base. A third vertical standard 3 is positioned on the base at one end in substantial alignment with standards 2—2.

The shaft 4 at one end extends beyond the adjacent pedestal 2 and has mounted thereon a freely rotatable pulley 5 provided with an annular clutch flange 6 and secured on the shaft by suitable washers 7 and 8 by a collar 9 secured on the shaft by a set screw 9'. A clutch member 10 is slidably mounted on shaft 4 as by feather 11 between the adjacent pedestal and pulley 5. The clutch member 10 is provided with a plurality of radial fingers 12 adapted to engage the annular clutch flange 6 of pulley 5 and the clutch is provided with a peripheral groove 13 in which is positioned ring 14 secured to clutch lever 15 which is pivotally secured to the base as by screw 16. A resilient arm 17 is rigidly secured to the base as by screw 18 and its upper end engages the hub of clutch 10 so as to damp the rotation of the clutch upon the release of the clutch. A collar 19 is fixedly secured to shaft 4 as by set screw 20, to secure the clutch and pulley assembly with respect to the adjacent pedestal 2.

On the opposite end of the main shaft 4 is slidably mounted a sleeve 21 having at its ends peripheral flanges 22 and 23. A ring 27 surrounds sleeve 21 being associated with arm 28 which terminates in a threaded boss 29. The ring 27 is secured against axial movement on sleeve 21 by collar 24, secured on the sleeve as by set screw 25.

The threaded boss 29 of arm 28 is threadedly mounted on the threaded portion of a rod 30 which is slidably mounted parallel with main shaft 4 in adjacent standards 2 and 3. This rod 30 has on its inner end a cam follower 36 and the boss 29 is provided with a set screw 31, by means of which its adjustment upon the threaded shaft 30 can be secured. A coiled spring 32 is positioned on the rod 30 between pedestal 3 and a cross pin 31' by means of which rod 30 is resiliently pressed in the direction of cam follower 36. The outer end of rod 30 is provided with a threaded section upon which is mounted lock nuts 34 and the rod is further provided with a knurled knob 35 by means of which it can be adjusted.

A resilient bumper 33 is positioned on rod 30 between lock nuts 34 and standard 3.

On the outer end of sleeve 21 a lug 37 is secured to flange 23 and the lower end of this lug projects into an axial slot 40 in the free end of shaft 4. A hook engaging hood 41 having a hook engaging slot 42 with an inclined bottom 43 is adjustably secured to flange 23 by means of screws 38 positioned in slotted flanges 39 which extend on opposite sides of hood 41.

The hook H as indicated by dotted lines in Figure 5 is adapted to be positioned with its shank in slot 40 and the hook part resiliently held in the slot 42 of hood 41 by means of the inclined bottom 43 of said slot. The entire sleeve 21 with its associated hood 41 is slidable upon shaft 4, and is rotated with the shaft by the engagement of lug 37 in the slot 40. Sliding of sleeve 21 upon shaft 4 will feed hook H outwardly with respect to shaft 4 within the slot.

The shank of the hook H is held in shaft 4 near its outer end by a pin 90 slidably mounted in the shaft transversely of slot 40. This pin 90 has a rounded inner end and is resiliently pressed across slot 40 as by spring 91.

Positioned on base 1 intermediate standards 2-2 and in transverse alignment with shaft 4 are two standards 50-50, upon which is mounted transverse cam shaft 51 upon one end of which is mounted cam 52 secured as by set screw 53, which cam is positioned to engage cam follower 36 on the end of rod 30. Between standards 50-50 a worm gear 54 is freely mounted on cam shaft 51 and this worm gear 54 engages a worm 55 formed on shaft 4. The worm gear 54 is provided with an annular flange 56 formed with inwardly directed gear teeth 57. Adjacent worm gear 54 a disc 58 is fixedly mounted on cam shaft 51 as by feather 59 and on this disc are mounted diametrically opposed dogs 60 biased by springs 61 secured to posts 62 against the gear teeth 57. Mounted on cam shaft 51 and also between standards 50-50 are two similar cam discs 68 and 65, one of which, 68, is fixedly secured to cam shaft 51 as by set screw 64 and the other, formed as an annular flange on sleeve 66, is rotatable with respect to shaft 51. Both of the cam discs 68 and 65 are formed with similar high and low portions 66' and 67', which are semi-circumferential in extent so that by varying the angular adjustment of these two cam discs with respect to each other the relative lengths of the effective high and low cam portions of the two discs regarded as a common cam can be modified as desired. On the outer end of sleeve 66 is an annular flange 67 provided with a plurality of spaced orifices 90 arranged circumferentially. On the outer end of cam shaft 51 is a disc 69 having a flange 70 and fixedly secured to shaft 51 as by set screw 71. The disc 69 is provided with an orifice 72 threaded to receive a screw 73 having a knurled head 74, which screw 73 is adapted to be selectively entered into one of the spaced orifices of flange 67 by which means it will be apparent that the rotary adjustment of disc 69 as by hand spokes 77 secured thereto will operate to angularly adjust cam discs 68-65 while the rotation of plate 69 when said plate is secured to flange 67 by screw 70 73 will operate to rotate combined cam discs 68-65 in unison, such rotation, however, being possible only in one direction by reason of the ratchet and dog connection between disc 58 and worm wheel 54. The cam discs 68-65 are engaged by a common cam follower 74 mounted on

a rod 75 slidably supported in standard 2 and connected to clutch lever 15 as by pin 76.

In operation it will be observed that the rotation of disc or control wheel 69 will rotate cam discs 68-65 from the inoperative position of the machine, in which cam follower 74 is set against the low cam surfaces and clutch 10 is disengaged from pulley 5 to bring the high cam surface in contact with cam follower 74 and thus engage clutch 10 and start the rotation of shaft 4 which will continue until the follower 74 again drops against the low cam surface. It will further be observed that the relative lengths of the high and low cam surfaces can be adjusted by means of the same control wheel 69 by adjusting same annularly with respect to flange 67 thus modifying the angular relationship of discs 68-65.

A pin 78 mounted on the base is adapted to receive a spool S containing the thread T for use with the machine and the spool S is damped by means of a coiled spring 79 secured against same as by pin 80 passing through post 78. The thread T is extended from spool S through a guide coil 81 secured to the base and thence between hard polished washers 82 mounted on a post 83 secured to pedestal 3 by a bracket 87. The tension of the washers 82 is controlled by a compression spring 84, the force of which is adjustable by means of cottapin 85 and its selective insertion into one of a plurality of holes 86 in rod 83. From washers 82 the thread is extended through a slot 88 in the bracket 87.

The end of the thread is given a counterclockwise turn about the shank of the hook and associated gut and then passed under a tension finger 45 secured in the end of shaft 4 and provided with a knife edge 45', which can be used at the conclusion of the wrapping operation to sever the thread T, preliminary to a repeat operation.

In operation the fish hook to be snelled is placed with its shank in slot 40 and with the hook caught under anvil 41 as indicated in Figure 5. The thread T is carried from spool S through the guide 81 and between the washers 82 and under the catch 45 on the end of the shaft. A length of gut or cord is then placed in slot 40 over the hook shank.

By turning disc 69 by hand spoke 77, shaft 51 is then rotated until the cam formed by the combined discs 65 and 68 engages roller 74 thus engaging the main clutch 10 and starting the machine. The machine continues operation as long as that cam rides against roller 74, which will be determined by the size of the cam, which in turn, is determined as previously pointed out by the angular relationship of cam discs 65 and 68.

During the operation of the machine the cam 52 will bear against follower 36, thus propelling carriage 21 outwardly and providing for the even spiral winding of the thread around the superposed shank and gut.

As previously indicated, the drawings herein represent a practical embodiment of the invention but various modifications will readily suggest themselves to those skilled in the art but within the scope of the invention as claimed.

Having thus fully described my invention, I claim:

1. In a machine for snelling fish hooks including a main rotatable shaft having means on one end for holding a fish hook, a free pulley on the shaft having a clutch element, a complementary clutch element slidably but non-rotatably mounted on the shaft, a cam rotatable by the shaft having an adjustable dwell and a follower for the

cam operatively connected to the slidable clutch element.

2. The device of claim 1 in which the cam comprises concentrically mounted discs each having peripheral dwells and means for angularly adjusting said discs to vary the relationship of said dwells with respect to each other.

3. The device of claim 1 in which the cam comprises two discs mounted on a shaft each having a peripheral dwell, one disc secured to the shaft, the other having a hub rotatable on the shaft, a disc flange on the hub having a plurality of spaced circumferentially arranged orifices, a complementary disc fixedly mounted on the shaft and a pin removably mounted on said disc to selectively engage one of the said circumferential orifices.

4. The device of claim 1 in which the cam is a disc mounted on a shaft, an over-running drive between said cam shaft and the main shaft and manually operable means for rotating the shaft in the counterdrive direction to bring the dwell of the cam into clutch releasing position.

5. The device of claim 1 in which the main shaft is provided with a worm and the cam is mounted on a shaft, a worm gear freely mounted on the cam shaft, said worm gear having ratchet teeth and dogs mounted on a member fixed to the shaft whereby the cam shaft is rotatable by the main shaft in one direction only and manually operable means for rotating the shaft in a counterdrive direction to bring the cam dwell into clutch releasing position to stop the machine.

6. The device of claim 1 in which the main shaft is provided with a worm, and the cam comprises two discs each having a peripheral dwell, said cam discs mounted on a shaft, one fixedly and the other rotatably, a member fixedly mounted on the cam shaft formed with hand grasps and carrying means for adjustably engaging the rotatable cam member, a worm gear rotatably mounted on the cam shaft engaging the worm of the main shaft and having ratchet teeth and means fixedly mounted on the cam shaft having dogs engaging said ratchet teeth.

ALEXANDER LAUTERBACH.
